UNITED STATES PATENT OFFICE.

WILLIAM L. JUHRING, OF BROOKLYN, NEW YORK.

DESIGN FOR A BOTTLE.

SPECIFICATION forming part of Design No. 23,380, dated June 19, 1894.

Application filed May 22, 1894. Serial No. 512,126. Term of patent 7 years.

To all whom it may concern:

Be it known that I, WILLIAM L. JUHRING, a citizen of the United States, residing in the city of Brooklyn, county of Kings, and State of New York, have invented and produced a new and original Design for Bottles, of which the following is a specification.

In the drawings:—Figure 1, is a side elevation of my design. Fig. 2, is a sectional view of the same.

My design consists in the configuration or shape of the bottle shown which as will appear from the drawings includes a protruding central portion *a* tapering to a neck portion

b of smaller diameter which has a flaring rim *c*. 15
The central portion *a* tapers more gradually toward the bottom of the bottle forming a depression *d* and from this the bottle flares outwardly to the base *e*.

I claim—

The design for bottles herein shown and described.

In testimony whereof I affix my signature in presence of two witnesses.

WILLIAM L. JUHRING.

Witnesses:

J. ROBERT FENTON,
F. J. DESSORI.
